UNITED STATES PATENT OFFICE.

ANDREW J. SANFORD, OF NEWARK, OHIO.

DESIGN FOR A LIGHT-SHADE.

40,474.

Specification for Design. Patented Jan. 25, 1910.

Application filed June 21, 1909. Serial No. 503,573. Term of patent 14 years.

To all whom it may concern:

Be it known that I, ANDREW J. SANFORD, a citizen of the United States, residing at Newark, in the county of Licking and State of Ohio, have invented a new, original, and ornamental Design for Light-Shades, of which the following is a specification, reference being had to the accompanying drawing, forming a part thereof.

The drawing is a perspective view of a glass shade showing my new design.

Its leading features comprise a main body portion on a substantially even flare and a skirt portion below it. The body portion is provided with a peculiar prismatic ornamentation consisting in a series of longitudi-

nal substantially diamond-shaped prisms alternating with a series of like prisms extending above them and with a series of V-shaped prisms extending below them. The skirt portion is decorated by a series of substantially diamond-shaped prisms alternating with a series of substantially V-shaped prisms, as shown.

I claim:

The ornamental design for a light shade as shown and described.

ANDREW J. SANFORD.
